US00D857689S

(12) **United States Design Patent** (10) **Patent No.:** **US D857,689 S**
(45) **Date of Patent:** **** Aug. 27, 2019**

(54) **KIOSK SYSTEM**

- (71) Applicant: **Zivelo Inc.**, Scottsdale, AZ (US)
(72) Inventor: **Zubair Birgeoglu**, Scottsdale, AZ (US)
(73) Assignee: **Zivelo LLC**, Scottsdale, AZ (US)

(**) Term: **15 Years**

(21) Appl. No.: **29/593,706**

(22) Filed: **Feb. 10, 2017**

Related U.S. Application Data

- (60) Continuation of application No. 29/513,996, filed on Jan. 7, 2015, now Pat. No. Des. 780,744, which is a division of application No. 29/414,671, filed on Mar. 1, 2012, now Pat. No. Des. 721,695.

(57) **CLAIM**

The ornamental design for a kiosk system, as shown and described.

DESCRIPTION

FIG. 1 is a top, front, and right side perspective of an embodiment of a kiosk system embodying my new design. FIG. 2 is a front view of the embodiment of FIG. 1. FIG. 3 is a back view of the embodiment of FIG. 1. FIG. 4 is a right side view of the embodiment of FIG. 1. FIG. 5 is a left side view of the embodiment of FIG. 1. FIG. 6 is a bottom view of the embodiment of FIG. 1. FIG. 7 is a top view of the embodiment of FIG. 1. FIG. 8 is a top, front, and right side perspective of another embodiment of a kiosk system embodying my new design. FIG. 9 is a front view of the embodiment of FIG. 8. FIG. 10 is a back view of the embodiment of FIG. 8. FIG. 11 is a right side view of the embodiment of FIG. 8. FIG. 12 is a left side view of the embodiment of FIG. 8. FIG. 13 is a bottom view of the embodiment of FIG. 8. FIG. 14 is a top view of the embodiment of FIG. 8. FIG. 15 is a top, front, and right side perspective of another embodiment of a kiosk system embodying my new design. FIG. 16 is a front view of the embodiment of FIG. 15. FIG. 17 is a back view of the embodiment of FIG. 15. FIG. 18 is a right side view of the embodiment of FIG. 15. FIG. 19 is a left side view of the embodiment of FIG. 15. FIG. 20 is a bottom view of the embodiment of FIG. 15; and, FIG. 21 is a top view of the embodiment of FIG. 15.
